US0D1004564S

(12) **United States Design Patent** (10) **Patent No.:** **US D1,004,564 S**
(45) **Date of Patent:** **** Nov. 14, 2023**

(54) **MOBILE PHONE**

(71) Applicant: **VIVO MOBILE COMMUNICATION CO., LTD.**, Chang'an Dongguan (CN)

(72) Inventor: **Hui Liu**, Chang'an Dongguan (CN)

(73) Assignee: **VIVO MOBILE COMMUNICATION CO., LTD.**, Chang'an Dongguan (CN)

(**) Term: **15 Years**

(21) Appl. No.: **29/748,562**

(22) Filed: **Aug. 31, 2020**

(30) **Foreign Application Priority Data**

Mar. 10, 2020 (CN) 202030077132.0
